Primary Examiner — Mitchell Siegel*(74) Attorney, Agent, or Firm* — Muncy, Geissler, Olds & Lowe, P.C.(57) **CLAIM**

The ornamental design for a coldness/heat preserving container, as shown and described.

DESCRIPTION

FIG. 1 is a perspective view of the coldness/heat preserving container showing my design;

FIG. 2 is a front elevational view thereof;

FIG. 3 is a rear elevational view thereof;

FIG. 4 is a top plan view thereof, the bottom plan view being identical thereto;

FIG. 5 is a right side view, the left side view being identical thereto;

FIG. 6 is a cross-section taken across line 6-6 of FIG. 4;

FIG. 7 is another top plan view thereof; and,

FIG. 8 is a cross-section taken across line B-C-D-E-F-G of FIG. 7.
